ASH TRAY OR SIMILAR ARTICLE

Herman Gadow, Jr., R.R. 1, Maynard, Iowa 50655

Filed Mar. 7, 1966, Ser. No. 1,327

Term of patent 14 years

(Cl. D85—2)

FIG. 1 is a perspective view of an ash tray showing my new design wherein the base includes the letter A connected to an arcuate rocker portion;

FIG. 2 is an enlarged scale right side elevational view;

FIG. 3 is an enlarged scale top plan view;

FIG. 4 is an enlarged scale elevational view, rotated 90° clockwise from the position of FIG. 2;

FIG. 5 is a bottom plan view of the unit shown in FIG. 2;

FIG. 6 is a perspective view of an ash tray showing my new design wherein the base includes the letter M connected to an arcuate rocker portion;

FIG. 7 is a bottom plan view of the unit of FIG. 6;

FIG. 8 is a perspective view of an ash tray showing my new design wherein the base includes the letter N connected to an arcuate rocker portion;

FIG. 9 is a bottom plan view of the unit of FIG. 8;

FIG. 10 is a perspective view of an ash tray showing my new design wherein the base includes the letter V connected to an arcuate rocker portion;

FIG. 11 is a bottom plan view of the unit of FIG. 10;

FIG. 12 is a perspective view of an ash tray showing my new design wherein the base includes the letter H connected to an arcuate rocker portion; and

FIG. 13 is a bottom plan view of the unit of FIG. 12. The common features of the five illustrated embodiments of my new design consists primarily in the standard having an arcuate rocker base portion, a top handle and an ash receptacle on the standard between the handle and the base.

I claim:

The ornamental design for an ash tray or similar article, substantially as shown and described.
